DRESSER COMPENSATING MECHANISM FOR
GRINDING MACHINESAugust F. Markus, Detroit, Mich., assignor to Ex-
Cell-O Corporation, Detroit, Mich., a corpora-
tion of Michigan

Application August 28, 1944, Serial No. 551,479

10 Claims. (Cl. 51—95)

The present invention is intended for application to grinding machines such, for example, as thread grinders, and has particular reference to grinding machines incorporating that general class of mechanisms known as automatic dressing compensators which serve to modify automatically the relative displacement of grinding wheel and work by an amount requisite to compensate for the diminishment in wheel size necessarily incident to each dressing or truing of the same.

One object of the present invention is to provide a grinding machine arranged to employ movement of a floatingly mounted cylinder for effecting relative movement between wheel and work supports of the machine and in which a piston within the cylinder is rigid with a non-rotatable nut threaded on a screw so that such screw may be revolved for size control purposes and shifted bodily endwise for dresser compensation.

Another object of the present invention is to provide a grinding machine embodying a work support pivoted to be rocked toward and from a grinding wheel by a suitable size control device, together with a novel arrangement for also rocking said work support compensatingly in accordance with the shift of an independently pivoted dresser support toward and from the wheel.

The invention also resides in various novel relations and combinations of the parts by means of which effective and reliable operation is accomplished with a simple, rugged mechanism.

Further objects and advantages of the invention will become apparent as the following description proceeds, taken in connection with the accompanying drawings, in which:

Figure 1 is a front elevation of a thread grinding machine embodying the present invention;

Fig. 2 is a vertical sectional view through the upper portion of the machine and taken substantially along the pivotal axis of the work support;

Fig. 3 is an end elevation, partially in section along the line 3—3 in Fig. 2 of the upper portion of the machine;

Fig. 3a is a detail sectional view taken substantially along the line 3a—3a in Fig. 3;

Fig. 4 is a view similar to Fig. 3 but somewhat more diagrammatic in character and showing the dresser support and retract cylinder in section; and

Fig. 5 is a fragmentary detail perspective view of the mount for the wheel support.

While the invention is susceptible of various modifications and alternative constructions, I have shown in the drawings and will herein de-

scribe in detail the preferred embodiment, but it is to be understood that I do not thereby intend to limit the invention to the specific form disclosed, but intend to cover all modifications and alternative constructions falling within the spirit and scope of the invention as expressed in the appended claims.

Referring more particularly to the drawings of the exemplary embodiment of the invention herein disclosed, it will be seen upon reference to the drawings that the same has been illustrated as embodied in a thread grinding machine (Fig. 1). Such machine comprises a base 10 on the top of which is a work support, designated generally as 11, and including centers 12 and 14 between which a work piece (indicated at W in Fig. 2) is received and presented to a rotatively driven grinding wheel 15. Truing of the grinding wheel periphery by some suitable form of dresser, various ones of which are available in the art, is requisite from time to time as the wheel periphery becomes misshapen by wear. The present invention is concerned primarily with an arrangement for automatically effecting a relative relocation of work and wheel upon each dressing of the latter in order to compensate for the diminution in wheel diameter necessarily incident to dressing. Such compensating arrangement is, however, so closely integrated with the related portions of the machine that a description of the latter, including the work support, wheel support, dresser support, etc., is desirable as a preface, even though the details of the same may be widely varied, without departing from the present invention.

In the illustrated machine, the work support 11 is of the form disclosed in a grinding machine covered by my copending application Serial No. 542,719, filed June 29, 1944. In this exemplary construction the work support includes a main frame 16 (Figs. 2 and 3) having an integral upstanding headstock end plate 17 at one end and longitudinally extending guideways 18 on the opposite end and on which the adjustably clamped tailstock 19 is received. Such frame 16 is slidable axially along a pair of aligned guide bars 20, 21 and is adapted to be rocked or pivoted about such bars to carry the work toward and from the grinding wheel 15. The guide bars 20, 21 are fixed in respective pairs of upstanding lugs 22, 23 and 24, 25 integral with the base 10. Depending integral feet 26, 27 on the work support frame 16 are bored to receive respective ones of the guide bars, the frame being translatable along such bars to shift the work axially, as well

as rockable about such bars for moving the work transaxially with reference to the grinding wheel.

A work supporting spindle 28 (Fig. 2) is journaled in the headstock of the work support 11 by antifriction bearings 29, 30, the latter bearing being carried by a tubular extension 31 in a gear housing 32 removably fixed to the upright plate 17. To effect translation of the work support frame 16 in timed relation with the rotation of the spindle 28, the latter is equipped with a replaceable master lead screw 33 threaded in a non-rotatable nut 34 carried by a supplemental or auxiliary head, designated generally as 35. This auxiliary head is mounted for rocking motion in unison with the work support frame 16 but is restrained against translation with the latter. Thus the auxiliary head 35 includes a frame 36 having a depending foot 37 journaled on a sleeve 38 within the hollow guide bar 20 and located at one side of the upstanding lug 22 on the base 10. On the opposite side of this lug is a block 39 fixed to the frame 36 and journaled on the guide bar 20. The frame 36 is thus mounted to pivot about the axis of the guide bar 20 but is restrained against movement endwise of the latter by the abutment of the foot 37 and block 39 with opposite sides of the lug 22. Within the upper portion of the frame 36 is a sleeve 40 journaled for rotative adjustment and having the nut 34 removably fixed to its outer end. The tubular extension 31 on the gear case housing 32 is slidably telescoped within this sleeve 40 so that the frames 16 and 36 are compelled to pivot in unison about the axis of the guide bars 20, 21, irrespective of their relative axial displacement. Rotational adjustment of the sleeve 40 is accomplished by a handwheel 41 fixed to a worm 42 meshed with an annulus of worm gear teeth formed at 43 in the periphery of the sleeve, such rotational adjustment being utilized in determining the lead pick-up. A sheet metal housing 44 encloses the outer end of the auxiliary head 35.

Rotation of the work spindle 28 and its feed screw 33 is accomplished from a drive shaft 45 (Fig. 2) disposed concentrically with the axis of tilting or pivotal motion of the work support about the guide rods 20, 21 so that the drive connections will remain undisturbed during all tilting movement of the latter. This shaft 45 is journaled within the tubular sleeve 38 heretofore mentioned and is driven by a worm gear 46 fixed to its outer end and meshed with a worm 47. The latter worm is, in turn, connected by a pulley 48 and a belt 49 with an electric drive motor 50 (Fig. 1) fixed to the lower portion of the machine base 10. A pinion 51 fixed to the drive shaft 45 meshes with a gear 52 carried by a shaft 53 journaled within the block 39. To complete a drive connection for revolving the spindle 28, the shaft 53 has a sliding spline connection 54 with a shaft 55 journaled in the main frame 16 and carrying a gear 56. The latter meshes with a second gear 57 rigid with a sleeve 58 keyed to the spindle 28.

Tilting motion is imparted to the work support frame 16 (and to its connected auxiliary head 35) through the use of an intermediate support or apron 59 which underlies the frame 16 (Figs. 2 and 3). This intermediate support is pivoted by integral upstanding legs 60, 61 on it on the guide bars 20, 21, so that it may rock coaxially with the work support frame 16 but is restrained against endwise movement with the latter. A taper control bar 62 (Fig. 3 and see

also Fig. 1) adjustably clamped to the front face of the work support frame 16 rests in sliding engagement with the upwardly projecting nose of a pin 63 carried on the intermediate support 59, the overhanging weight of the work support retaining contact between the bar and pin at all times. As described in more detail in my co-pending application, Serial No. 542,719, referred to above, provision may, if desired, be made for adjusting the angle of the bar 62 longitudinally of the same to impart rocking motion to the work support relative to the intermediate support in timed relation with the translation of the former for use in grinding tapered shapes, and likewise provision may be made for automatically raising and lowering the pin 63 through use of an eccentric cam disk 64 driven in timed relation with the rotation of the spindle 28 in accomplishing relief grinding. Such refinements, however, form no part of the present invention and consequently need not be examined except for the observation that the compensating arrangement hereinafter described does not interfere in any way with their function.

Bodily endwise movement of a floatingly mounted cylinder 65 (Figs. 3 and 4) is utilized for rocking the pivoted intermediate support 59, together with the work support carried by the latter. Such cylinder constitutes a portion of a rapid-retraction mechanism and has a piston 66 slideable therein, the cylinder itself being slidably mounted in the present instance within a tubular extension 67 integral with a bracket 68 fixed to the machine base 10. The cylinder is connected to a pair of laterally spaced depending feet 69, integral with the underside of the intermediate support, by a pair of links 70 (see also Fig. 2). Such links are pivoted at their respective opposite ends to such feet and to the cylinder. Assuming for the moment that the piston 66 is held stationary in some manner, it will be seen that if pressure fluid is admitted to the right end of the cylinder 65 through the port 71 and exhausted from the opposite end through the port 72 that the cylinder will be shifted to the right from the position shown in Fig. 4, thereby rocking the intermediate support and work support counterclockwise to withdraw the work rapidly from the grinding wheel 15. Conversely, admission of pressure fluid through the port 72 and exhausting of fluid from the other port 71 will thrust the cylinder 65 to the left, thereby rocking the work back toward the grinding wheel. A suitable source of pressure fluid and control valve (not shown) for supplying and exhausting pressure fluid to and from the cylinder 65 may of course be provided. In the present instance it is intended that the hydraulically effected movement of the cylinder 65 be used in effecting rapid retraction of the work at the completion of grinding and restoration of the work to position for re-institution of grinding. Normally the fluid is locked in the cylinder 65 so that the cylinder is compelled to move in unison with the piston when the latter moves.

Provision is made herein for moving the piston 66 axially, while carrying the cylinder 65 with it, in order to rock the intermediate and work supports both for size control and dresser compensation purposes. With that in view the piston 66 is made rigid with a nut 73 keyed within the cylinder 65 to restrain such nut against rotation and threaded on a screw 74. The nut 73 and its attached piston 66 may, accordingly, be displaced

axially either by rotating the screw 74 or shifting the latter bodily in an axial direction. In the present machine rotation of the screw is used for size control purposes and bodily endwise movement of the same for dresser compensation.

A size control mechanism, designated generally as 75, is shown herein as mounted on the base 10 and arranged to revolve the screw 74, such mechanism being splined to the screw so that the latter may have freedom of axial movement. In the present instance the size control mechanism includes a manually rotatable size control wheel 76 for rotating the screw. Normally the size control mechanism is used for rocking the work step-by-step toward the grinding wheel in timed relation with the reciprocations of the work to and fro past the wheel so that the grinding may be carried out in successive increments to a predetermined depth. If desired, a ratchet type actuating mechanism, such for example, as that disclosed in Guenther Brinkmann application, Serial No. 435,224, filed March 18, 1942, and assigned to Ex-Cell-O Corporation, assignee of this present application, may be enclosed in the housing of the size control mechanism for automatic power actuation of the screw 74 to turn the same step-by-step in effecting the desired infeed of the work in timed relation with reciprocation of the work support.

Turning now to the matter of the mounting of the grinding wheel 15 and its associated dresser mechanism, it will be observed upon reference to Figs. 3 and 4 that the grinding wheel is carried by a wheel support designated generally as 77. Such wheel support includes a central rectangular plate-like portion 78 having integral therewith a pair of upstanding side walls or arms 79 between the upper ends of which the grinding wheel 15 is journaled. The lower portions of these side walls are joined by a web 80 integral therewith as well as with the plate 78. Beneath this web is pivotally mounted a bracket 81 carrying a drive motor 82 connected by a belt 83 with the grinding wheel for revolving the latter.

The wheel support 77 is mounted on the machine base 10 for adjustment axially of the work, as well as for limited angular adjustment in accommodating respectively positioning of the wheel for operation on various longitudinally displaced portions of the work and various helix angles for the threads to be ground on the work. For purposes of such adjustments, accurately machined flat surfaces 84, 85 are provided on the machine base 10 and wheel support 77, respectively, a rectangular block 86 (see also Fig. 5) being sandwiched between these surfaces. This block presents accurately machined parallel opposite side faces and is releasably secured to the base 10 by bolts 87 passing through slots 88 extending longitudinally of the surface 84, the block 86 being accurately guided for adjustment movement axially of the work piece by a key 89. The wheel support 77 is, in turn, similarly secured to the block 86 by bolts having their heads received in T-slots 90 which are in this instance arcuate. Adjustment movement of the wheel support with reference to the block is accurately guided by an arcuate key 91. The key 91 and slots 90 are centered about a line passing through the axes of the work and grinding wheel. Both lateral and angular adjustment of the grinding wheel 15 can thus be accomplished readily and with precision. It will be understood that the range of angular adjustment need only be quite small, that is, of the order of about 5°.

A dresser mechanism, designated generally as 75 of movement. A hydraulic type arrangement

92 (Figs. 3 and 4), for the grinding wheel 15 is carried on a dresser supporting frame 93 pivoted at 94 to the wheel support 77 so that the dresser mechanism moves bodily with the wheel and wheel support during adjustments in position of the latter, thereby obviating any necessity for relocation of the dresser as an incident to such adjustments. The dresser mechanism as such may take a variety of forms and may, for example, be like that disclosed in some detail in Gilbert Stewart Patent No. 2,311,263, issued February 16, 1943. In brief, it comprises one or more diamond dresser points 95 mounted on the dresser frame 93 for movement with reference to the latter in a predetermined cycle of movement in which the point or points approach the grinding wheel, engage its periphery to true the same to predetermined contour, and thereafter withdraw out of contact with the wheel back to their starting position. Movement of the dresser supporting frame 93 thus serves to shift the mean location of the path of movement for the dresser points with reference to the grinding wheel and thereby determine the dressed diameter of the wheel, the dresser support being shifted toward the wheel a predetermined increment as a preliminary to each successive dressing operation.

In the construction shown (Figs. 3 and 4) the dresser supporting frame 93 is of inverted L-shape with depending side walls 96 and is pivoted at 94 between the side walls 79 of the wheel support, the pivotal axis of the dresser support being parallel with the axis of rotation of the grinding wheel.

A screw 97 (Fig. 4) is used for rocking the dresser supporting frame 93 about its pivot 94 toward the grinding wheel 15 transaxially of the latter. Such screw is threaded in a tubular projection 98 on an upstanding plate 99 integral with the outer end of the web 80 of the wheel support 77. A tension spring 100 anchored at its opposite ends to the plate 99 and to the dresser supporting frame 93 retains the latter in contact with the nose of the screw 97. For manual operation of the screw 97 a dresser control wheel 101 is fixed to its outer end and may be revolved to advance or retract the dresser supporting frame a desired amount. In some instances it may be desirable to turn the screw 97 automatically step-by-step in coordination with the cycling of the dresser mechanism. In such case a ratchet wheel 102 is provided which is rigid with the hub of the control wheel 101. A pawl 103 is pivoted on an oscillatable pawl carrier 104 journaled on the cylindrical portion of the plate 99 coaxially with the screw. A guard plate or shield 105 overlying a portion of the periphery of the ratchet wheel may be locked in adjusted position by a thumb nut 106 to overlie a selected portion of the teeth otherwise exposed to the pawl and thus determine the angular distance through which the ratchet wheel is advanced at each stroke of the pawl in correspondingly determining the length of each step-by-step advance for the dresser supporting frame 93. The pawl carrier 105 is oscillated by a plunger 107 reciprocable within a bore 108 in the plate 99. Any suitable means may be provided for actuating this plunger in timed relation with the cycling of the dresser mechanism 92, the arrangement being in general such that the dresser supporting frame 93 is rocked forward toward the wheel 15 through a predetermined increment of distance preparatory to the execution by the dresser mechanism of each of its successive cycles

suitable for such timed actuation of the plunger 107 is disclosed for example in Ira J. Snader Patent No. 2,251,961, issued August 12, 1941, and accordingly further detailing here is unnecessary.

In the dresser compensating mechanism herein disclosed provision is made for shifting the work support 11 coincidentally with each movement of the dresser supporting frame 93 in a manner such that the work is repositioned relative to the wheel 15 by an amount substantially equal to the diminishment in wheel diameter occasioned by the advance of the dresser supporting frame. For that purpose the dresser supporting frame 93 is mechanically connected by a suitable linkage to the screw 74 coaxing with the floating cylinder 65 so that the latter will be displaced axially by an amount sufficient to rock the work support 11 through a distance corresponding to each displacement of the dresser supporting frame 93.

In the illustrative construction the linkage between the dresser supporting frame 93 and the screw 74 includes a yoke 109 (see Figs. 2 and 3) pivoted coaxially with the intermediate support 59 and work support 11 on the guide bar 21. Extending between the upstanding arms of this yoke is a rod 110 which is slidably pivoted one end of a link 111 extending rearwardly toward the dresser frame and pivoted to the latter at 112. By utilizing a sliding connection (including the rod 110 as shown) between the link 111 and yoke 109, bodily adjustment of the wheel and dresser supports longitudinally of the work is accommodated without interruption of the linkage connection. For a similar purpose, a ball and socket type swivel joint 111a is interposed in the link 111 intermediate its ends, thus accommodating the angular adjustment of the wheel support relative to the work.

Depending from the yoke 109 is an integral arm 109a (see Fig. 2) having pivoted thereto a pair of links 113 which are pivoted at their forward ends to a collar 114 (see Fig. 4) journaled on the end of the screw 74 and held on the latter to move axially with the same by an abutting shoulder 115 and an opposed nut 116. The pivot points for the pairs of links 70 and 113 for connecting the same, respectively, to the intermediate support 59 and yoke 109 are located equidistantly from the axis of the guide rod 21, in order to minimize the effect of angular displacement between the intermediate support and yoke upon change in wheel diameter. With the dresser supporting frame 93 linked to the floating cylinder 65 as described, it will be seen that upon each advance or retreat of the dresser supporting frame the screw 74 will be correspondingly displaced axially, thereby carrying with it the floating cylinder 65 and causing the intermediate and work supports to be rocked through a commensurate distance.

In the operation of the grinding machine disclosed, the operator may turn the dresser control wheel 101 until the dresser supporting frame 93 is rocked forward a sufficient distance for effective engagement of the dresser point or points with the grinding wheel. Then the dresser mechanism may be cycled to dress the wheel periphery to a desired shape for the grinding operation to follow. Pressure fluid is admitted through the right-hand port 71 of the cylinder 65 to thrust the piston 66 to the left and thus rock the intermediate and work supports 59, 11 clockwise for rapid approach of the work into adjacency with the grinding wheel. The motor 50 revolves and traverses the work in timed relation through the drive con-

nections heretofore described and the size control mechanism 75 is utilized to rock the work step-by-step transaxially toward the wheel in timed relation with the reciprocations of the work, all in the usual manner, until a thread of desired depth has been ground in the work. At such times as may be required, the cylinder 65 is shifted relative to the piston 66 to withdraw the work from the wheel and the dresser mechanism 92 is caused to execute a cycle of movement for dressing the wheel. Preparatory to each such cycling of the dresser mechanism, the screw 97 is revolved a predetermined distance to rock the dresser supporting frame forward for a desired increment of dresser feed. As the dresser supporting frame 93 swings forward the link 111 thrusts the yoke 109 clockwise about its pivotal axis. Such movement of the yoke in turn thrusts the screw 74 axially to the left, the latter carrying the piston and cylinder 66, 65 with it. Accordingly, the intermediate and work supports are rocked clockwise to advance the work relative to the wheel, the geometry of the parts being such that the advance of the work thus effected is substantially precisely equal to the diminishment of wheel size which will result from the coincident advance of the dresser supporting frame 93.

I claim as my invention:

1. In a grinding machine, the combination of relatively movable work and wheel supports, said wheel support carrying a rotatively driven grinding wheel, a rotatable screw having a nut threaded thereon with the latter restrained against rotation, a fluid operated piston rigid with said nut and slidably endwise within a floatingly mounted cylinder, the admission of pressure fluid to alternate ends of said cylinder serving to displace said cylinder endwise of said screw and travel of said nut axially of said screw as an incident to rotation of the latter serving to carry said cylinder in a direction endwise of said screw, size control means for revolving said screw, and means mechanically connecting said cylinder to one of said supports for moving the latter relative to the other support in accordance with movement of said cylinder in a direction endwise of said screw.
2. In a grinding machine, the combination of a base, work and wheel supports, the latter having a rotatively driven grinding wheel thereon, means pivotally mounting said work support on said base for rocking of the same toward and from said wheel generally transaxially of the latter, size control means for rocking said work support, a dresser support pivoted on said wheel support to rock toward and from said wheel, means operable in accordance with changes in position of said dresser support with reference to said wheel support for correspondingly rocking said work support, and means for effecting bodily adjustment as a unit of said wheel support and the dresser support pivoted thereon to vary the angle of said wheel with reference to a work piece carried by said work support.
3. In a grinding machine, the combination of a base, work and wheel supports, the latter having a rotatively driven grinding wheel thereon, means pivotally mounting said work support on said base for rocking of the same toward and from said wheel generally transaxially of the latter, size control means for rocking said work support, a dresser support pivoted on said wheel support to rock toward and from said wheel, and means operable in accordance with changes in position of said dresser support with reference to said

wheel support for correspondingly rocking said work support.

4. In a grinding machine, the combination of a base having relatively movable work and wheel supports mounted thereon, the latter carrying a rotatively driven grinding wheel, a rotatable screw having a nut threaded thereon with the nut restrained against rotation, size control means for revolving said screw to cause said nut to travel axially therealong, connecting means for connecting said nut to one of said supports for moving the latter relative to the other support upon endwise displacement of said nut, said connecting means including a fluid operated piston and cylinder for moving said one support relative to the other support between two alternatively available limit positions independently of movement of said nut, a dresser support movable toward and from said wheel, and means for displacing said screw endwise in accordance with changes in position of said dresser support to thereby shift said nut and the connected one of said first-mentioned supports accordingly.

5. In a grinding machine, the combination of a base having a wheel support thereon carrying a rotatively driven grinding wheel, a work support pivoted on said base for rocking motion generally transaxially of said wheel, a rotatable screw having a nut threaded thereon with the nut restrained against rotation, size control means for revolving said screw to cause said nut to travel axially therealong, connecting means for connecting said nut to said work support for rocking the latter toward and from said wheel in accordance with endwise displacement of said nut, said connecting means including a fluid operated piston and cylinder for moving said work support toward and from said wheel between two limit positions independently of any movement of said nut, a dresser support movable toward and from said wheel, and means for displacing said screw endwise in accordance with changes in position of said dresser support to thereby shift said nut and the connected work support accordingly.

6. In a grinding machine, the combination of relatively movable work and wheel supports, said wheel support carrying a rotatively driven grinding wheel, a rotatable screw having a nut threaded thereon with the latter restrained against rotation, a fluid operated piston rigid with said nut and slidably endwise within a floatingly mounted cylinder, the admission of pressure fluid to alternate ends of said cylinder serving to displace said cylinder endwise of said screw and travel of said nut axially of said screw as an incident to rotation of the latter serving to carry said cylinder in a direction endwise of said screw, size control means for revolving said screw, means mechanically connecting said cylinder to one of said supports for moving the latter relative to the other support in accordance with movement of said cylinder in a direction endwise of said screw, a dresser support adjustable toward and from said wheel, and means mechanically connecting said screw to said dresser for endwise displacement of said screw in accordance with adjustment in dresser support position and to restrain said screw against endwise displacement when said dresser support is at rest.

7. In a grinding machine, the combination of a base having a wheel support thereon carrying a rotatively driven grinding wheel, a work support pivoted on said base for rocking motion generally transaxial of said wheel, a rotatable screw having

15 a nut threaded thereon with the nut restrained against rotation, a fluid operated piston rigid with said nut and slidably endwise within a cylinder floatingly mounted on said base, admission of pressure fluid to alternate ends of said cylinder serving to displace the latter endwise of said screw and travel of said nut axially of said screw as an incident to rotation of the latter serving to carry said cylinder in a direction endwise of said screw, size control means for revolving said screw, and a linkage connecting said cylinder to said work support for rocking of the latter toward and from said wheel in accordance with movement of said cylinder in a direction endwise of said screw.

20 8. In a grinding machine, the combination of a base having a wheel support thereon carrying a rotatively driven grinding wheel, a work support pivoted on said base for rocking motion generally transaxial of said wheel, a rotatable screw having a nut threaded thereon with the nut restrained against rotation, a fluid operated piston rigid with said nut and slidably endwise within a cylinder floatingly mounted on said base, admission of pressure fluid to alternate ends of said cylinder serving to displace the latter endwise of said screw and travel of said nut axially of said screw as an incident to rotation of the latter serving to carry said cylinder in a direction endwise of said screw, size control means for revolving said screw, a linkage connecting said cylinder to said work support for rocking of the latter toward and from said wheel in accordance with movement of said cylinder in a direction endwise of said screw, a dresser support adjustable toward and from said wheel, and means mechanically connecting said screw to said dresser support for endwise displacement of said screw in accordance with adjustment in dresser support position and to restrain said screw against endwise displacement when said dresser support is at rest.

25 9. In a grinding machine, the combination of a base having a wheel support thereon carrying a rotatively driven grinding wheel, a work support disposed at one side of said grinding wheel, means mounting said work support on said base for rocking of said work support generally transaxially of said wheel and for translation of said work support in a path generally paralleling the wheel axis, an intermediate support underlying said work support with the latter resting on the same, means mounting said intermediate support on said base for movement about a pivotal axis coincident with the pivotal axis of said work support but with the intermediate support restrained against translation, a screw extending transversely beneath said intermediate support and having a nut threaded thereon with the nut restrained against rotation, a fluid operated piston rigid with said nut and slidably endwise within a floatingly mounted cylinder, the admission of pressure fluid to alternate ends of said cylinder serving to displace the latter endwise of said screw, and travel of said nut axially of said screw as an incident to rotation of the latter serving to carry said cylinder in a direction endwise of said screw, size control means for revolving said screw, said intermediate support having a depending leg thereon, linkage pivotally connecting said leg to said cylinder for rocking of said intermediate support about its pivot in accordance with endwise movement of said cylinder, a dresser support adjustable toward and from said wheel, and a second linkage connecting said dresser support to said screw for bodily endwise displacement of the latter in ac-

cordance with changes in position of said dresser support.

10. In a grinding machine, the combination of a base having a wheel support thereon carrying a rotatively driven grinding wheel, a work support disposed at one side of said grinding wheel, means mounting said work support on said base for rocking of said work support generally transaxially of said wheel and for translation of said work support in a path generally paralleling the wheel axis, an intermediate support underlying said work support with the latter resting on the same, means mounting said intermediate support on said base for movement about a pivotal axis coincident with the pivotal axis of said work support but with the intermediate support restrained against translation, a screw extending transversely beneath said intermediate support and having a nut threaded thereon with the nut restrained against rotation, a fluid operated piston rigid with 10 said nut and slideable endwise within a floatingly mounted cylinder, the admission of pressure fluid

5 to alternate ends of said cylinder serving to displace the latter endwise of said screw, and travel of said nut axially of said screw as an incident to rotation of the latter serving to carry said cylinder in a direction endwise of said screw, size control means for revolving said screw, said intermediate support having a depending leg thereon, linkage pivotally connecting said leg to said cylinder for rocking of said intermediate support about its pivot in accordance with endwise movement of said cylinder, a dresser support adjustable toward and from said wheel, a second depending leg of a length equal to the first-mentioned one and pivoted to swing on an axis coincident with the common pivotal axis of said intermediate and work supports, and linkage means interconnecting said dresser support and said screw through said second leg for bodily displacement of said screw in an endwise direction in accordance with changes in position of said dresser support.

AUGUST F. MARKUS.
